(57) **CLAIM**

The ornamental design for a wok station, as shown and described.

DESCRIPTION

FIG. 1 is a perspective view of a wok station according to my new design;

FIG. 2 is a front view of the wok station of FIG. 1;

FIG. 3 is a top view of the wok station of FIG. 1;

FIG. 4 is a right side view of the wok station of FIG. 1;

FIG. 5 is a left side view of the wok station of FIG. 1;

FIG. 6 is a bottom view of the wok station of FIG. 1; and,

FIG. 7 is a rear view of the wok station of FIG. 1.

All features shown in broken lines form no part of the claimed design. The bottom and rear views of FIGS. 6 and 7 are provided for reference only and form no part of the claimed design.

1 Claim, 3 Drawing Sheets
